(57) **CLAIM**

The ornamental design for the loudspeaker, as shown and described.

DESCRIPTION

The present design pertains to an acoustic transducer that may be used as a loudspeaker or may be used with other components in a loudspeaker system.

FIG. 1 is a top left and front perspective view of a loudspeaker showing our new design;

FIG. 2 is a left side elevational view thereof, the right side elevational view being a mirror image;

FIG. 3 is a front elevational view thereof; and,

FIG. 4 is a top plan view thereof, the bottom plan being a mirror image.

The broken line showing on the drawing disclosure is for illustrative purposes only and forms no part of the claimed design.

1 Claim, 2 Drawing Sheets

FIG. 2**FIG. 3**
